UNITED STATES PATENT OFFICE.

TOLBERT LANSTON, OF WASHINGTON, DISTRICT OF COLUMBIA, ASSIGNOR, BY DIRECT AND MESNE ASSIGNMENTS, TO THE LANSTON TYPE MACHINE COMPANY, OF SAME PLACE.

PRODUCING JUSTIFIED LINES OF TYPE.

SPECIFICATION forming part of Letters Patent No. 364,523, dated June 7, 1887.

Original application filed September 30, 1885. Serial No. 178,671. Divided and this application filed July 3, 1886. Serial No. 207,158.
(No model.)

To all whom it may concern:

Be it known that I, TOLBERT LANSTON, of Washington, in the District of Columbia, have invented certain new and useful Improvements 5 in the Art of Forming Justified Lines of Types; and I do hereby declare the following to be a full, clear, and exact description of the same, reference being had to the accompanying drawings, forming part of this specification, 10 and to the figures and letters of reference marked thereon.

This case is a division of an application filed by me September 30, 1885, No. 178,671. In another division of said application—*i. e.*, No. 15 207,156—filed contemporaneously herewith, I have shown and described certain improvements in the art of producing justified lines and forms of types, and in illustration thereof have disclosed several modes of carrying my said invention into practice. One of said modes forms 20 the subject-matter of the present application, and, broadly stated, consists in first ascertaining the amount of space required to be filled up by justification, if types of normal or standard 25 size were used, and then forming successively the types that are to compose the line, the printing-types of normal width and the space-types of a width varying in proportion to the ascertained amount of space required to be 30 filled out or absorbed by justification.

Referring to the accompanying drawings, Figure 1 is a diagrammatic view representing an unjustified line of types of normal or standard dimensions, upon an enlarged scale, the 35 outlines only of the types being shown; Fig. 2, a similar view representing a justified line of the same characters made in accordance with my invention. Fig. 3 is a view of a portion of a form of types constructed in accordance with my invention.

Similar letters and numbers in the several figures indicate corresponding parts.

Referring particularly to Fig. 1, let the interval between the points lettered *a* and *c* represent 45 the length of the proposed line of composition, assumed to be the width of the column, the interval between *a* and *b* the space which

would be occupied by the unjustified line of types of normal or standard size, and the interval between *b* and *c* the space to be filled by justification. Having thus ascertained the amount of space to be absorbed in justifying the given line, and the number of space-types in said unjustified line, I proceed to form successively the series of types, making each printing-type of normal size and the space-types of a width varying in proportion to the ascertained amount of space required to be filled out or absorbed. This is illustrated in Fig. 2, wherein 2, 4, 6, 8, 13, 16, and 21 represent space-types, which are made of a width increased above the corresponding normal types shown in Fig. 1, an amount equal to the space *b c* divided by the number of space-types employed—*i. e.*, seven; or, in other words, 65 each of said space-types is increased one-seventh of the space *b c*. This mode of procedure is followed in the production of each line of matter, the result being that the types made for each line will exactly fill that line, irrespective of the character of the composition. 70

I have not thought it necessary to describe herein any special mechanism for carrying my invention into effect. A competent mechanism for the purpose is, however, described in 75 my before-mentioned application, No. 178,671.

Having thus described my invention, what I claim as new is—

The hereinbefore-described improvement in the art of forming justified lines of type, consisting in first ascertaining the amount of space required to be filled up by justification, if types of normal or standard size were used, and then forming successively the types that are to compose the line, the printing-types of normal width and the space-types of a width varying in proportion to the ascertained amount of space required to be filled out or absorbed by justification. 85

TOLBERT LANSTON.
